UNITED STATES PATENT OFFICE.

OSCAR ZUMFT, OF KINDERHOOK, NEW YORK.

DESIGN FOR A GASLIGHTER.

Application filed March 19, 1923. Serial No. 5,517. Term of patent 3½ years.

To all whom it may concern:

Be it known that I, OSCAR ZUMFT, a citizen of the United States, residing at Kinderhook, in the county of Columbia and State of New York, have invented a new, original, and ornamental Design for a Gaslighter, of which the following is a specification, reference being had to the accompanying drawing, forming a part thereof.

The figure is a perspective view of a gas lighter showing my design.

I claim:

The ornamental design for a gaslighter, as shown.

OSCAR ZUMFT.
